United States Patent Office.

JOHN P. SHERWOOD, OF FORT EDWARD, NEW YORK, ASSIGNOR TO HIMSELF AND BENJAMIN S. BURNHAM, OF SAME PLACE.

Letters Patent No. 98,199, dated December 21, 1869.

IMPROVED WASH-BOILER.

The Schedule referred to in these Letters Patent and making part of the same.

To all whom it may concern:

Be it known that I, JOHN P. SHERWOOD, of Fort Edward, in the county of Washington, and State of New York, have invented a new and useful Improvement in Washing-Boilers; and I do hereby declare that the following is a full, clear, and exact description thereof, which will enable others skilled in the art to make and use the same, reference being had to the accompanying drawings, forming part of this specification, in which—

Figure 1 is a vertical longitudinal section of my improved boiler, taken through the line *xx* of fig. 2.

Figure 2 is a vertical cross-section of the same, taken through the line *yy*, fig. 1.

Similar letters of reference indicate corresponding parts.

My invention has for its object to improve the construction of that class of washing-boilers in which the clothes are washed by the water as it boils, being projected down upon the clothes, to percolate through them, and thus remove the dirt; and

It consists in the combination, with the perforated false-bottom, of the end discharge-spouts, of peculiar construction, as will be hereinafter more fully described.

A represents an ordinary wash-boiler, about the construction of which there is nothing new.

B is a false bottom, which is placed a little above the bottom of the boiler *A*, so as to leave a space below it for the water.

The water-space below the false bottom *B* is divided into two compartments by the cross-partition *C*, the upper edge of which is attached to the said false bottom *B* at or near its middle, and the lower edge of which rests upon the bottom of the boiler *A*. When the fire is hotter under one part or end of the boiler than it is under the other end, the tendency is for the water to be drawn toward the hotter end of the boiler, and be discharged through the spout at that end, leaving the other spout inactive. The partition *C* guards against this tendency, and secures the circulation of the water through both spouts, though in volumes proportioned to the difference in heat of the two ends of the boiler.

The false bottom *B* is corrugated longitudinally upon each side of its central line, with two upwardly-projecting corrugations, *b*, as shown in figs. 1 and 2,

extending from one end of said bottom to the other, so as to form channels for the hottest part of the water and the steam to pass to the end spouts *D*.

The part of the false bottom *B* between and at the sides of the corrugations *b*, is perforated with numerous holes, to allow the water to flow back freely to the space beneath the false bottom *B*.

The parts of the false bottom *B* toward its ends are made without perforations, so that the water may flow through said bottom only along its middle part, thus introducing the cooler water over the middle or hottest part of the fire, and also preventing the cooler water from mingling with the water as it is about passing up the end spouts *D*.

The spouts *D* pass up the ends of the boiler *A*, with the form of which ends the outer sides of the said spouts correspond. The inner sides of the spouts *D* incline outward, so that the said spouts may become narrower as they approach the top of the boiler *A*.

The upper ends *d* of the spouts *D* are inclined inward and downward, as shown in fig. 1, and are made broad and tapering.

The under side of the inwardly and downwardly-projecting parts *d* of the spouts *D* are corrugated, the said corrugations beginning at or near the angle or bend of the spouts, and gradually increasing in depth, until, at the ends of the spouts, they touch the upper sides of the said spouts, thus dividing the streams of water into a series of thin sheets, which, flowing from the spouts at the two ends of the boilers, meet, and are spread over the entire surface of the clothes, thoroughly removing the dirt from all their parts.

Having thus described my invention,

I claim as new, and desire to secure by Letters Patent—

The two end spouts, *D*, having their inwardly-projecting upper parts *d*, constructed in the manner herein shown and described, in combination with the corrugated and perforated false bottom *B*, substantially as and for the purpose set forth.

JOHN P. SHERWOOD.
